UNITED STATES PATENT OFFICE.

WILLIAM H. SIMONS, OF COLUMBUS, OHIO.

PORCH-SWING.

1,094,028.

Specification of Letters Patent. Patented Apr. 21, 1914.

Application filed September 5, 1913. Serial No. 788,318.

To all whom it may concern:

Be it known that I, WILLIAM H. SIMONS, a citizen of the United States, residing at Columbus, in the county of Franklin and State of Ohio, have invented certain new and useful Improvements in Porch-Swings, of which the following is a specification.

The present invention relates to improvements in porch swings and is designed to provide a convertible swing that may also be used as a child's crib, when desired.

The object of the invention is to combine the features of a swing and a crib in the same device in such manner that the combination device may be converted for use as desired, with facility and despatch. By the utilization of the principles of my invention in this character of device, I provide a simple, practical, and inexpensive device that will perform the functions of a swing or crib in a most satisfactory manner.

In the accompanying drawings I have illustrated one complete example (and a modification thereof) of the physical embodiment of my invention constructed according to the best mode I have so far devised for the practical application of the principles of the invention.

Figure 1 is a transverse sectional view of the device, fashioned as a porch swing. Fig. 2 is a similar sectional view of the same device, fashioned as a child's crib. Fig. 3 is a front elevation of one end of the porch swing as seen in Fig. 1. Fig. 4 is a perspective view of a portion of one of the connecting links, showing its double-T end. Fig. 5 is a sectional view of a modification of the invention.

In the preferred embodiment of my invention the swing is provided with the front and rear rails 1 and 2 respectively, which connect the end bars 3 and rear corner posts 4. The usual handle bars 5 and front posts 6 are present, and the slats 7, 7, are used for the seat and back of the swing, as well as for the ends thereof. These described parts are of suitable wood and proper size, and are fastened together in any of the usual styles suitable for this purpose.

In adapting my invention to the convertible device I provide an extension 8 at the upper ends of the rear posts 4, and each post is fashioned with a T-slot 9 as clearly seen in Fig. 3. This slot 9 is for the reception of a complementary T-head 10, or a

similar head 11 at the end of a link 12. The link 12 is pivoted at 13 to a bar 14, which in turn is hinged at 15 to a bracket 16. There are two of the pairs of hinged or pivoted links 12 and bars 14, one at each end 60 of the swing, and the pairs of bars 14 are connected by slats 17 similar to the slats 7 in construction and function.

When used as a swing the pivoted links and bars are turned back on their hinges 65 15, the bars 14 and slats 17 being in position under the swing and out of the way, while the links 12 are located directly back of the rear posts 4 with the T-heads 10 protruding through the T-slots in the extension 70 8 of the posts 4.

To convert the swing into a child's crib, the heads 10 of the links 12 are first lifted from the vertical to the horizontal part of the slots 9 and then withdrawn therethrough. 75 The links 12 and bars 14 are then swung around under the swing on their pivots 13 and 15, into the position of Fig. 2, and the T-heads 11 are then passed through the horizontal portion of the T-slots 9 and dropped 80 down into the vertical slots, the projecting heads serving to lock the device in position.

In the modification in Fig. 5 the crib attachment comprises the slatted side portion 17' whose end bars 18 are dropped down in 85 the guide grooves 19 of the end front posts 20 when the device is to be used as a crib. When not in use the attachment is located at the underside and rear of the swing with the bars 18 pushed from the rear in the 90 grooved cleats 21, one at each end of the swing. This attachment forms a slide gate with end bars 22 that may be placed in position with facility, and when not needed may be stored out of the way in the grooved 95 cleats.

In Fig. 2 it will be seen that the bars 14 and slats 17 form an efficient swinging gate, that is held securely locked by the heads 11 and slotted extensions 8, when the device is 100 used as a crib, and when not used for this purpose, the gate with its links 12 may be swung out of the way, and out of sight, and locked, when the device presents to view a swing of ordinary and usual appearance. 105

From the above description taken in connection with the drawings it is believed, the novel features of my invention will be apparent, and the meritorious and advantageous characteristics will be evident. 110

Having thus fully described my invention, what I claim is:—

1. The combination with a porch swing having extended, slotted rear end posts, of a gate hinged to the swing, a link at each end of the gate, and a head on each link adapted to interlock with one of said slotted extensions.
2. The combination with a porch swing having a T-slotted rear post at each end, of a gate hinged at the front of the swing, a link pivoted at each end of the gate, and a pair of T-heads on each link adapted to fit said slotted posts.
3. The combination in a convertible porch swing including its rear posts, of a gate pivoted to the swing and provided with locking

links and means for locking said posts and links together, whereby the gate may be stored under the swing and operatively held 20 in front of the swing.

4. The combination in a convertible porch swing including slotted portions at its rear, of a gate pivoted to the swing and provided with a pair of locking heads adapted to fit 25 the slotted portions, for the purpose described.

In testimony whereof I affix my signature in presence of two witnesses.

WILLIAM H. SIMONS.
